Primary Examiner — George J Ulsh*Assistant Examiner* — Christine Tucci(57) CLAIM

The ornamental design for a women's round neck casual suit as shown and described.

DESCRIPTION

FIG. 1 is a front and right perspective view of a women's round neck casual suit, showing my new design;

FIG. 2 is a rear and left perspective view thereof;

FIG. 3 is a front view thereof;

FIG. 4 is a rear view thereof;

FIG. 5 is a left view thereof; and,

FIG. 6 is a right view thereof.

The broken lines in the drawings depict portions of the women's round neck casual suit that form no part of the claimed design.
